In the Netherlands July 29, 1949

5 Claims. (Cl. 315—21)

1

This invention relates to circuits comprising a cathode-ray tube having means for producing and deflecting a cathode-ray beam, in which a collecting electrode system is connected to a deflection electrode such that the beam is adapted to occupy any of a plurality of naturally stable positions, and in which means are provided for displacing the beam from one stable position to a subsequent position.

In a known circuit of this kind the beam is held fast in the various stable positions in that in each position the beam current is divided between a first collecting electrode and a further collecting electrode. The first collecting electrode is, on the one hand, connected directly to a deflection electrode and, on the other hand, by way of a resistance to a source of supply. In a position of equilibrium a current flows to the first collecting electrode and through the resistance so as to produce such deflection voltage as is required to maintain the beam at this position.

If, for some reason or other, the beam is slightly deflected from a position of equilibrium and if it moves, for example, towards the first collecting electrode, the current flowing through this electrode and the resistance increases. The deflection voltage is thus varied in such a sense that the movement is counteracted and the beam is driven back to the position of equilibrium concerned.

In a further known circuit the cathode-ray tube comprises a plurality of collecting electrodes connected to taps on a potentiometer, one end of which is coupled to a deflection electrode. The taps are chosen to be such that, if the beam strikes one collecting electrode, a deflection voltage is produced such as is required to direct the beam to the electrode concerned.

In a modified form of this circuit the potentiometer also serves as a collecting electrode, which in this case is constructed as a resistance electrode having a resistance varying in a step-wise manner in the direction of deflection.

In these circuits different deflection voltages correspond to the respective stable positions. The beam may be moved from one stable position to a subsequent position by supplying a pulse to the deflection system. This object may be attained in known manner by deflecting the beam with the use of separate deflection electrodes in a direction such that the beam leaves the stable position and moves automatically to a subsequent position. As an alternative, a pulse may be superposed on the stabilizing deflection voltage so that this voltage is suddenly altered to have a value

2

which, at least approximately, corresponds to that associated with a subsequent position of equilibrium.

Such circuits are particularly suitable to be used for counting purposes, for example in a calculating machine, since the position of the beam provides an indication of the number of pulses supplied to the circuit.

As a rule, the number of stable positions is ten, so that the number of pulses may be recorded in a decimal system.

In order to move the beam back, to a predetermined initial position after all the stable positions have been traversed successively, use is made of an auxiliary collecting electrode which is struck by the beam in an extreme position and which has derived from it a pulse which is supplied to the deflection system or to an intensity-control electrode of the tube and which brings about fly-back of the beam. During fly-back, the deflection voltage varies in such manner that the beam automatically moves to its initial position.

In practice a need is felt for a tube designed to record in a given numerical system and exhibiting, for example, ten stable positions, which may also be used with a different numerical system such that the beam is moved back to the initial position after, for example, every 9 or 8 pulses.

According to the invention, this object is attained in that the deflection electrode which stabilizes the beam is coupled by way of a rectifier to a source of voltage whose magnitude is adjustable.

During fly-back, the deflection voltage varies and the beam moves towards the "natural" initial position of the beam.

When a predetermined deflection voltage is exceeded, the rectifier becomes conductive, so that the deflection voltage cannot vary to such extent that the beam can fall within the attraction sphere of the natural initial position. The beam then falls within the attraction sphere of another stable position which then fulfills the function of an initial position.

In order that the invention may be clearly understood and readily carried into effect, it will now be described in detail by reference to the accompanying drawing, wherein:

Fig. 1 shows a circuit in which the beam is stabilized by means of division of current, and

Fig. 2 shows a diagram with the use of which the operation of the circuit will be explained.

The cathode-ray tube T in Fig. 1 comprises

cathode and focussing electrode means 2 and 3 known per se and shown here only diagrammatically, for producing a cathode-ray beam, a set of deflection plates 4 and 5 for deflecting the beam, and collecting electrodes 6, 7, 12. The electrode 6 is arranged in front of the electrode 7 and has a number of apertures such that the beam upon being deflected alternately strikes an element of the electrode 6 and, through an aperture of this electrode, an element of the electrode 7.

The current flowing to the electrode 7 then varies as a function of the deflection voltage at the deflection electrode 5, as shown by curve 21 in Fig. 2. If the beam falls through an aperture of the electrode 6, the full beam current flows to the electrode 7. If, however, the beam is intercepted by the electrode 6, the current flowing to the electrode 7 is zero.

The electrode 7 is connected through a conductor 8 to the deflection electrode 5, which is furthermore coupled by way of a resistance 10 to the positive terminal of a battery 11.

The negative terminal of the battery is connected to the cathode 2 of the cathode-ray tube. The collecting electrode 6 is directly connected to the positive terminal of the battery. A suitable voltage is supplied to the deflection electrode 4, which co-operates with the electrode 5 in a manner which is not shown.

The relation between the current traversing the resistance 10 and the voltage of the electrode 5 is shown by the straight resistance line 20 in Fig. 2. If the resistance is not traversed by current, the voltage equals the battery voltage V_b . Upon increasing current the voltage at the point 9 decreases.

In a position of equilibrium the current traversing the conductor 8 equals the current traversing the resistance 10, which implies that the positions of equilibrium of the beam are required to correspond to intersections of the curves 20 and 21 in Fig. 2.

The intersections 22, 23, 24, 25, 26, 27 correspond to stable positions of the beam, whereas the intersections 28, 29, 30, 31, 32 provide unstable positions of equilibrium of the beam. This may be appreciated from the following:

It is assumed that at a given moment the voltage at point 9 is V_2 . The current flowing through the conductor 8 then exceeds the current flowing through the resistance 10. Owing to the difference in current, the natural capacity or condenser coupled to the point 9 and designated C in Fig. 1 is discharged. The voltage of point 9 will thus decrease and the beam moves towards the stable position of the beam corresponding to the intersection 26. Similar reasoning applies if the voltage is slightly lower than the voltage V_1 corresponding to the intersection 26. Consequently, the beam will automatically move to this stable position if the voltage of the point 9 lies within the interval between the voltages V_3 and V_4 corresponding to the metastable positions of equilibrium 31 and 32. This interval thus constitutes the "attraction sphere" of the stable position 26. Similarly, the voltages exceeding the voltage V_5 corresponding to the metastable position 29 are associated with the attraction sphere of the natural initial position 22. The figure shows, by way of example, only 6 stable positions. It is evident that the number may also be greater or smaller.

As already mentioned before, in practice use is mostly made of ten positions. The beam may be

moved from a stable position to a subsequent position by supplying to the point 9 a pulse such that the voltage of point 9 is abruptly varied to have a value which lies within the attraction sphere of the desired subsequent stable position.

As an alternative, a pulse may be supplied to the deflection electrode 4 in a manner as described in the copending U. S. application S. N. 790,874, filed December 10, 1947.

It is assumed that the beam originally occupies the initial position 22. The first pulse then moves the beam to position 23 and after five pulses the beam has reached the position 27. The beam is moved back to the initial position by the sixth pulse. This process is accomplished as follows.

In the tube an auxiliary collecting electrode 12 is arranged at the side of the collecting system 6, 7 in such manner that this electrode is struck by the beam after the sixth pulse. This results in the electrode 12 being charged in a negative sense. The negative voltage pulse is transferred by way of a condenser 13 and the conductor 8 to the deflection electrode 5, with the result that the beam in first instance is even further driven onto the electrode 12. After a short time the electrode 12 is charged and the capacity C, which is coupled with the point 9, starts to discharge so that the beam will move in the opposite direction, that is to say in the direction of the collecting system 6, 7.

As soon as the beam leaves the electrode 12, this electrode is discharged by way of a resistance 14, which is attended with a strong positive voltage pulse. This positive pulse is transferred by way of the condenser 13 to the deflection electrode 5, so that the voltage of the point 9 is abruptly increased to a value higher than that of the voltage V_5 so that the beam comes within the attraction sphere of the initial position 22 and will move to this position.

In the example here given, the beam thus returns to the initial position after every six pulses.

In order to permit fly-back of the beam after an arbitrarily smaller number of pulses, use is made of a diode 15 which, if desired, may form part of the cathode-ray tube.

The anode of this diode is connected to the point 9, whereas the cathode is connected to a tap on a potentiometer 16, which is connected across the battery 11.

The diode becomes conductive if the voltage at the point 9 exceeds the voltage V_6 at the tap on the potentiometer. The latter voltage may be varied according to requirements by shifting said tap.

If the beam flies back after having struck the electrode 12, the operation of the diode has the effect of limiting the positive pulse supplied by way of condenser 12 to the deflection electrode 5. Consequently, the voltage at the point 9 cannot in practice exceed the voltage V_6 , which is shown by curve 33 in Fig. 2.

After this pulse has ceased, the voltage at the point 9 thus equals V_6 , which in the example shown lies within the attraction sphere of the stable position V_6 .

What I claim is :

1. An electronic circuit comprising a cathode-ray tube provided with an electron beam source, a collecting electrode system, deflecting electrodes for deflecting said beam along said system and a reset collecting electrode disposed to be struck by said beam in an extreme position

thereof, means coupling said system to one of said deflecting electrodes whereby said beam is adapted to occupy any one of a plurality of naturally stable positions along said system, means for displacing said beam from one stable position to a subsequent position means coupling said reset electrode to one of said deflecting electrodes whereby a pulse derived from said reset electrode displaces said beam to an initial position, a direct voltage source, a rectifier, and voltage adjusting means coupling said one of said deflecting electrodes to said voltage source through said rectifier.

2. An arrangement, as set forth in claim 1, wherein said rectifier is constituted by a diode having an anode and a cathode, and said voltage adjusting means is constituted by a potentiometer having a movable tap, the potentiometer being connected across said voltage source, said cathode being connected to said tap and said anode being connected to said one of said deflecting electrodes.

3. An electronic counting circuit comprising a cathode-ray tube provided with an electron beam source, first and second deflecting electrodes for deflecting said beam, first and second spaced collecting electrodes disposed in the path of the deflected beam and a reset collecting electrode disposed adjacent one end of said first collecting electrode, first and second resistances means to apply a constant voltage to said second collecting electrode and through said first resistance to said first collecting electrode, means to apply a constant voltage through said second resistance to said reset electrode, means connecting said first collecting electrode to said first deflecting electrode whereby said beam is adapted to occupy any one of a plurality of naturally stable positions along said collecting electrodes, means to apply an external voltage impulse to said second deflecting electrode to displace said beam from one stable position to another, a rectifier, means coupling said reset electrode to said first deflecting electrode whereby a pulse derived from said reset electrodes displaces said beam to an initial position, and means to apply a voltage of adjustable magnitude to said reset electrode through said rectifier.

4. An electronic counting circuit comprising a cathode-ray tube provided with an electron beam source having a cathode, first and second deflecting electrodes for deflecting said beam, first and second spaced collecting electrodes disposed in the path of the deflected beam and a reset collecting electrode disposed adjacent one end of said first collecting electrode, first and second resistances, a direct voltage source having its negative terminal connected to said cathode and its positive terminal connected to said second collecting electrode and through said first resistance to said first collecting electrode, said positive terminal being also connected through said second resistance to said reset electrode, means connecting said first collecting electrode to said first deflecting electrode whereby said beam is adapted to occupy any one of a plurality of naturally stable positions along said collecting electrodes, means to apply an external voltage impulse to said second deflecting electrode to displace said beam from one stable position to another, means coupling said reset electrode to said first deflecting electrode whereby a pulse derived from said reset electrode displaces said beam to an initial position, a potentiometer having a tap and connected across said source, and a rectifier connected between said first deflecting electrode and the tap on said potentiometer.
5. An arrangement, as set forth in claim 4, wherein said second collecting electrode is disposed in front of said first collecting electrode with respect to said beam source and is provided with spaced openings through which said beam impinges on said first collecting electrode.
